United States Patent Office

Des. 234,025
Patented Dec. 31, 1974

234,025

DISPOSABLE CULTURE DEVICE

Edward Potter, 2213 Waverly Place,
Waukegan, Ill. 62692

Filed Nov. 6, 1972, Ser. No. 304,887

Term of patent 14 years

Int. Cl. D24—02; D9—04

U.S. Cl. D32—1

FIG.1

FIG.2

FIG.3

FIG. 1 is a top plan view of a disposable culture device showing my new design;

FIG. 2 is a side plan view;

FIG. 3 is a perspective view showing the parts of the device.

I claim:

The ornamental design for a disposable culture device, substantially as shown and described.
